UNITED STATES PATENT OFFICE

2,456,640

ELECTRICAL APPARATUS BUSHING

Leonard J. Linde, Drexel Hill, Nicholas F. Arone,
Upper Darby, and Benjamin E. Spiro, Philadelphia, Pa., assignors to General Electric Company, a corporation of New York

Application September 14, 1944, Serial No. 554,100

5 Claims. (Cl. 174—152)

1

Our invention relates to electrical apparatus, such as circuit breakers or the like, wherein an insulated electrical conductor generally referred to as a bushing extends through a wall or cover of an electrical housing or the like. Specifically our invention is concerned with a new and improved electric bushing for electric circuit breakers or the like.

Bushings for electric circuit breakers, of the type particularly adapted for use with metal-clad switchgear, have been constructed by placing a conductor within a treated paper or fabric insulated tube. This insulated tube then was machined along a part of its length from one end thereof to produce a body portion of reduced cross section after which a flanged metal supporting cylinder was pressed over this reduced body portion. Finally an insulating sleeve for backing up the supporting cylinder was pressed over the remaining portion of reduced cross section. This construction required the close fitting together of the long machined surfaces of the several component cylindrical members, otherwise breakdown often resulted when high voltage impulses were applied.

Our invention is particularly concerned with providing a new and improved bushing for electric circuit breakers or the like and which, because the support therefor is fabricated, is simpler and less dependent upon the close fits of its component parts, and which arrangement results in a more satisfactory bushing.

It therefore is an object of our invention to provide an improved apparatus of this character, which apparatus shall be simple in construction, effective in use and inexpensive to manufacture.

Further objects and advantages of our invention will become apparent as the following description proceeds and the features of novelty which characterize our invention will be pointed out with particularity in the claims annexed to and forming a part of this specification.

For a better understanding of our invention reference may be had to the accompanying drawing in which Fig. 1 is an elevational view partly in section of an electric circuit breaker employing bushings embodying our invention; Figs. 2a, 2b, 2c, 2d and 2e illustrate successive steps in manufacturing the bushing embodying our invention; Fig. 3 is a sectional view taken on line 3—3 of Fig. 2e, and Fig. 4 is a view similar to Fig. 2e illustrating a modified bushing made in accordance with our invention.

Referring now to Fig. 1, we have illustrated our invention as applied to a well known form of cir-

2

cuit breaker which happens to be particularly adapted for use in metal-clad switchgear. This circuit breaker is in many respects similar to the circuit breaker disclosed and claimed in Linde Patent 2,293,513, granted August 18, 1942, and assigned to the same assignee as the present application. Such a breaker comprises a plurality of conductor studs or bushings such as 1 and 2, each provided with a suitable mounting flange so that the conductor stud or bushing may be supported where it passes through the wall or housing 3 of the circuit breaker, generally indicated at 4. The bushing 1 in the case of a breaker such as is disclosed in the Linde patent, is somewhat shorter than the bushing 2. We have illustrated the complete bushing 1 in Fig. 2e and the complete bushing 2 in Fig. 4.

The bushing 1 includes an axial conducting stud or core member 5 formed of copper or the like, 20 having a spherical plug type terminal 6 formed at one end thereof for engaging self-aligningly with a cooperating resilient socket type terminal. The end of conductor 5 opposite from terminal 6 is provided with a suitable configuration 7, so as to be adapted for connection to a contact such as the stationary contact of the circuit breaker 4. Except for the terminal 6 and the rectangularly configured portion 7, conductor 5 preferably comprises a cylindrical rod.

In order to insulate conductor 5 from the grounded portions of the circuit breaker 4 including the housing 3, the conductor 5 is first pressed into a cylinder or tube 8 of insulating material, the tube 8 being slipped over the end 6 of conductor 5 after an end thrust washer 7' has been placed upon the rod 5 for abutting the end portion 7 as indicated in Fig. 2a. Preferably this cylinder is constructed of laminated sheet organic material united by an adhesive binder. A portion of the cylinder 8 intermediate the ends thereof is undercut by machining so as to form a portion of reduced circular cross section 9. This step is preferably performed after the cylinder 8 is pressed around conductor 5. Fig. 2a illustrates the bushing after the machining operation on cylinder 8 is performed.

In Fig. 2b there is shown a perspective view of a pair of flanged semi-cylindrical metal members 10 and 11 which are constructed so as to fit 50 around the portion of reduced cross section 9 and completely envelop the same. The flanges 12 associated with the members 10 and 11 provide the means for supporting the conductor stud at the point where it passes through the wall or housing 3 of circuit breaker 4. The ends of the

semi-cylindrical members 10 and 11 preferably are tapered as indicated at 13 so that when they are applied to the insulating cylinder 8 they underlie the surface of the cylinder 8, thereby raising the corona point in this region of high electrical stress to a safe value thereby permitting the improved bushing constructed according to our invention to withstand the desired impulse voltages.

The next step in the process of constructing the bushing or conductor stud of our invention comprises cementing the semi-cylindrical flanged metal members 10 and 11 to the portion of reduced cross section 9 of cylinder 8. We have found that a phenolic modified polyvinyl butyral resin cement is very satisfactory for this purpose. This cement is applied to the holding surfaces and the semi-cylindrical members 10 and 11 then are clamped with pressure about the cylinder 8 and baked for approximately an hour at 250° C. in order to set the cement. The bushing or conductor stud with the flanged semi-cylindrical members cemented thereto is afterwards placed in a lathe to true up the cylindrical surfaces of the flanged members 10 and 11 as well as to insure that the mounting surfaces of the flanges 12 are perpendicular to the axis of the bushing. At the same time, an annular groove 14 is machined into the semi-cylindrical members, as is clearly indicated in Fig. 2c. The conductor stud or bushing disclosed in Fig. 2c illustrates the appearance thereof after the above steps in the process of manufacture have been performed.

In Fig. 2d there is illustrated a perspective view of a thin-walled metal tube 15, preferably formed of brass or the like, having an inside diameter such that it is readily slideable over the cylinder 8 and the true curved surfaces of the cemented halves 10 and 11. A small hole 16 is provided in one of the semi-cylindrical flanged members, as is clearly indicated in Fig. 3. The thin-walled metal cylinder 15 now is slid over the terminal end 6 of the conductor 5 to surround the semi-cylindrical members 10 and 11 above the flanges 12. To prevent this tube 15 from rotating, a portion of the tube indicated at 17 in Figs. 2e and 3 is indented into the hole 16 in the semi-cylindrical member 10. Thereafter the cylindrical tube or sleeve 15 is deformed by spinning it, as indicated at 18, into the annular groove 14 thereby producing a tightly gripping retaining ring which reinforces the cemented semi-cylindrical members 10 and 11. The now completed bushing, as indicated in Fig. 2e, is ready for installation in the circuit breaker 4 and for which purpose suitable mounting bolts are used which extend through the openings 19 in flanges 12 and through corresponding holes in the breaker housing 3.

In Fig. 4 we have illustrated the conductor stud or bushing 2 which is constructed in a manner very similar to the bushing 1 described above, except that the undercut portion of the insulating tube is somewhat longer and consequently the semi-cylindrical members are correspondingly longer. The conductor stud or bushing 2 also comprises a conducting rod having a spherical plug type terminal 20 at one end thereof and a suitable rectangularly configured portion 21 at the other end, which may be adapted so as to support the pivoted contact of the above-mentioned type electric circuit breaker. A thrust washer 22 is slipped over the terminal end 20 of the conducting member until it engages the portion 21, after which the insulating tube 23 is slipped

over the terminal 20 and pressed into position. As in bushing 1, the portion of reduced cross section 24 intermediate the ends of the insulating tube 23 preferably is machined after the tube 5 is assembled on the conducting member. The flanged semi-cylindrical members such as 25, only one of which is shown in Fig. 4 since the other is hidden from view, are then cemented to the portion of reduced cross section 24 after which these semi-cylindrical members are trued up in a lathe and the flanges 26 associated with the semi-cylindrical members 25 are machined on their mounting face so as to be truly perpendicular with the axis of the bushing. Also two annular grooves similar to the annular groove 14 of Fig. 2c are cut in the semi-cylindrical members, one above and one below the flanges 26. A clamping sleeve 27 substantially identical with clamping sleeve 15 is slipped over the terminal end 20 of the bushing 2 and held from rotating by an indentation 28 while the sleeve is deformed, as by spinning into the annular groove indicated at 29. Similarly a sleeve 30 is slipped over the other end of bushing 2 so as to clamp the lower ends of the semi-cylindrical members such as 25. The clamping sleeve 30 is also prevented from rotating by indenting a portion thereof as indicated at 31 into an opening formed in one of the semi-cylindrical members 25 after which the clamping sleeve 30 is deformed by spinning it into the associated annular groove, as indicated at 32.

It will be obvious that the above-described cementing method used in the manufacturing process of the bushing of our invention produces an exceedingly strong adhesive joint between the cylinder of insulating material and each curved portion of the flanged supporting members in order for these joints to withstand the strain from the subsequent intermediate machining, grooving and spinning operations as already described. Actually, we have found these cemented joints to be adequate for supporting the bushing through the agency of its composite flanged cylindrical supporting structure without benefit of any further reinforcement; so that the spun sleeves 15, 27 and 32 may be regarded rather as providing additional security for the flanged halves and also for imparting an appearance of solidarity to the finished product.

It will be appreciated from the above explanation that we have provided new and improved electric bushings which are simple to manufacture in that they eliminate the requirement of close fits which are difficult to maintain and which necessitates accurate and long machined surfaces. In addition the tapered portions 13 of the semi-cylindrical members 10 and 11 are effective in raising the corona point to a safe value whereby the bushings or conductor studs of our invention withstand higher impulse voltages than in comparable bushings as constructed heretofore.

Although we have disclosed particular embodiments of our invention, it will be obvious to those skilled in the art that modifications may be made without departing from our invention and we intend in the appended claims to cover all such changes and modifications as fall within the true spirit and scope of our invention.

What we claim as new and desire to secure by Letters Patent of the United States, is:

1. A terminal bushing for an electric switch comprising a conducting member including a terminal formed thereon, an insulating sleeve

having a reduced cross section portion intermediate the ends thereof enclosing a substantial portion of said conducting member, supporting means encircling said sleeve including a pair of flanged semi-cylindrical members cemented to said portion of reduced cross section, and a thin walled metal tube surrounding said semi-cylindrical members so as tightly to grip said members to reinforce the same.

2. A bushing for an electric switch comprising a conducting member, an insulating sleeve enclosing a substantial portion of said conducting member, supporting means encircling said sleeve including a pair of flanged semi-cylindrical members cemented to said sleeve, and a thin walled metal tube surrounding said semi-cylindrical members so as tightly to grip said members to reinforce the same.

3. A bushing for an electric switch comprising a conducting member, an insulating sleeve having a reduced cross section portion intermediate the ends thereof enclosing a substantial portion of said conducting member, supporting means encircling said sleeve including a pair of flanged semi-cylindrical members cemented to said portion of reduced cross section, a thin walled metal tube surrounding said semi-cylindrical members, and means for causing said tube tightly to grip and reinforce said semi-cylindrical members comprising an annular groove in said semi-cylindrical members and a cooperating deformed portion on said metal tube.

4. A bushing for electric apparatus comprising a central rod-like conducting core, an insulating cylindrical sleeve completely surrounding part of the length of said core, supporting means comprising a plurality of segmental component members arrayed circumferentially around a portion of said sleeve, each said member including a curved portion conforming to the curvature of said sleeve, cementing material interposed between said segmental members and said sleeve to form a bond therebetween, and a thin walled metal tube surrounding the curved

portion of said segmental members so as tightly to grip said members to provide reinforcement for the bond between said segmental members and said sleeve.

5. A bushing for electric apparatus comprising a central rod-like conducting core, an insulating cylindrical sleeve completely surrounding part of the length of said core, an annular recess around said sleeve, supporting means comprising a plurality of segmental component members arrayed circumferentially around said annular recess, each said member including a curved portion conforming to the curvature of said annular recess, cementing material interposed between said segmental members and said sleeve to form a bond therebetween and an indented metal tube surrounding the curved portion of said segmental members so as tightly to grip said members to provide reinforcement for the bond between said segmental members and said sleeve.
